United States Patent Office

Des. 207,808
Patented May 30, 1967

207,808

FLASK HOLDER OR SIMILAR ARTICLE

Hayden W. Coulthurst, Cranston, R.I., assignor to Textron Inc., Providence, R.I., a corporation of Rhode Island

Filed May 17, 1966, Ser. No. 2,328

Term of patent 14 years

(Cl. D58—26)

FIG. 1

FIG. 2

FIG. 3

FIG. 4

FIG. 5

FIG. 1 is a perspective view of a flask holder or similar article showing my new design;

FIG. 2 is a front elevational view;

FIG. 3 is a rear elevational view;

FIG. 4 is an end elevational view looking from the right of FIG. 1; and

FIG. 5 is a top plan view thereof.

I claim:

The ornamental design for a flask holder or similar article, substantially as shown.
